UNITED STATES PATENT OFFICE.

JOHN J. CONWAY, OF BRIDGEPORT, CONNECTICUT, ASSIGNOR TO THE ACME SHEAR COMPANY, OF BRIDGEPORT, CONNECTICUT, A CORPORATION OF CONNECTICUT.

DESIGN FOR A PAIR OF SCISSORS.

Application filed April 21, 1923. Serial No. 5,891. Term of patent 14 years.

To all whom it may concern:

Be it known that I, JOHN J. CONWAY, a citizen of the United States, residing at Bridgeport, in the county of Fairfield and State of Connecticut, have invented a new, original, and ornamental Design for a Pair of Scissors, of which the following as a specification, reference being had to the accompanying drawing, forming part thereof.

The figure is a plan view of a pair of scissors, showing my new design.

I claim:

The ornamental design for a pair of scissors, as shown.

Signed at Bridgeport, in the county of Fairfield, and State of Connecticut, this 19th day of April, 1923.

JOHN J. CONWAY.
